CARBOY HANDLING APPARATUS

Myron Bixler, Philadelphia, Pa.

Application September 2, 1944, Serial No. 552,551

6 Claims. (Cl. 248—142)

The present invention relates to handling apparatus and more particularly to the picking up, transporting and tilting of encased carboys.

Handling apparatus for carboys as heretofore in use necessitates lifting the carboys onto a truck or other wheeled vehicle and by reason of the bulky nature and heavy weight, this is not only difficult to accomplish, but introduces a hazard which often results in damage to the carboy or injury to the user. Furthermore, conventional carboy handling equipment has no provision for safe tilting of the carboy to discharge its contents, nor does it have such flexibility as will accommodate different sized carboys.

Some of the objects of the present invention are: to provide an improved support for encased carboys; to provide means for mounting an encased carboy upon a movable support as a complete unitary stable assembly; to provide a novel carboy attachment serving as a means for mounting the carboy upon a truck or other movable support whereby lifting of the carboy is unnecessary; to provide an adjustable mounting means capable of association with carboys of different size; to provide a novel carboy mounting means including provision for tilting the carboy in a safe and efficient manner; to provide a clamp for encased carboys so constructed and arranged that the carboy can be quickly mounted in the frame without lifting and rigidly held therein; to provide adjustable trunnion mountings in association with a carboy clamp for facilitating tilting of the carboy; and to provide other improvements as will hereinafter appear.

In the accompanying drawings, Fig. 1 represents a front elevation of a carboy having one form of clamp attached thereto ready for mounting upon a truck, the frame and truck embodying one form of the present invention; Fig. 2 represents a side elevation of the same; Fig. 3 represents a plan of the same; Fig. 4 represents an enlarged detail of the clamp lock and trunnion control; Fig. 5 represents an enlarged detail in plan of the parts shown in Fig. 4; Fig. 6 represents a perspective of the assembled carboy and clamp mounted upon one form of movable support; Fig. 7 represents a detail in plan of a means for interlocking the frame and truck to prevent improper tilting of the carboy; Fig. 8 represents a side elevation of the parts shown in Fig. 7; Fig. 9 represents a plan of the sill member of the clamp; and Fig. 10 represents a side elevation of the sill member showing the means for attaching the side members thereto.

Referring to the drawings, one form of the

present invention is shown for use with a carboy encased in the usual enclosing box 10 with the carboy neck 11 protruding through the customary hole 12 in the top 13 of the box. Also, the sides of the box 10 are provided with transversely disposed strips 14 forming hand grips for lifting the box when necessary, while the bottom of the box 10 is provided with two stringers 15 arranged in parallel to form feet for the box and which also provide a space 16 between the bottom of the box and the ground or floor.

For mounting the encased carboy, a clamp is provided formed by a bottom bar 17, two side standards 18, and an apertured head plate 20. Preferably, this clamp is collapsible by forming the ends of the bottom bar 17 with apertured forks 21 respectively to receive respectively apertured tongues 22 upon the respective lower ends of the standards 18. Pintles 23 are preferably attached by chains, cords, or like flexible means 24 to the respective standards 18, at a location convenient for insertion of the pintles 23 through the interfitting apertured parts, thus serving as hinges for the respective side standards 18. The chains 24 prevent the pintles 23 from being displaced or lost. The upper ends of the standards 18 terminate above the top of the box 10, and each is provided with a lug 25 having a row of downwardly disposed hooks 26 juxtaposed with respect to the side of the box adjacent thereto.

For locking the clamp about the box 10, the head plate 20 is provided at each end with a lever latch 27 pivoted at 28 and, in the present instance, having a slot 30 arranged to be engaged by one of the hooks on the lug 25. When the two latches 27 are so engaged, the tail 31 of each is pressed down toward the head plate 20 placing the standards 18 under tension and is then locked by swinging loop detents 32 into holding relation with the latch tails 31. The detents 32 are pivoted at the proper location upon the head plate 20 for the purpose intended. When the parts are so locked, the head plate 20 bears upon the top of the box 10 through the medium of a cushioning gasket 33, which encircles the neck 11 of the carboy.

In order to support the clamp with its mounted carboy, each standard 18 has a bracket 34 fixed thereto and extending laterally outward to form an end bearing for a threaded rod 35, the upper end of which has a bearing in the outwardly disposed end 36 of its standard 18. Motion is transmitted to the respective rods 35 by manually operated crank arms 37. Each rod 35 has a bushing 38 internally threaded thereon

and from which latter an arcuate trunnion 40 projects laterally to form a journaled support when seated in the arcuate seat 41 of the movable support. The opposite side of each bushing 38 is provided with a rectangular retainer 42 arranged for sliding movement in the ways formed by two spaced guides 43 attached to each side of the box 10. Thus, by turning the crank arms 37, the threaded rods 35 will feed the bushings 38 lengthwise of the rods 35 and thereby vary the vertical positions of the two trunnions 40. The movable support, in this instance, is in the form of a wheeled truck, formed by a U-shaped base 44, and two skeleton frames, each formed by two bars 45 converging to the top of a third vertical bar 46 to form a common support for the aforesaid trunnion seat 41.

For the purpose of preventing improper swing of the mounted carboy, each bracket 34 is provided with a hinged bifurcated catch 48 having a horizontal axis, and the bifurcation having a width to snugly straddle the rod 38. Thus, when the trunnions are seated in the seats on the truck frames, the catch 48 can be swung from its inoperative position resting upon the bracket 34 to its operative position straddling the rod 38 to thereby hold the carboy and its clamp against movement about the trunnions as an axis.

In assembly and operation, one of the pintles 23 is removed to release one standard 18 from the bar 17, whereupon the bar 17 can be inserted into the space 16 beneath the box 10, after which the standard 18 is replaced and attached by the pinte 23. The two standards 18 now parallel the sides of the box 10 in close proximity thereto, and the head plate 20 lowered over the protruding carboy neck to seat upon the cushioning gasket 33. The two latches 27 are now swung so that each engages under one of the hooks 25 in the adjacent series of hooks. The tails 31 of the latches are now swung downwardly to create the necessary locking pressure and are then fixed by bringing the detents 32 into holding position. The clamp is now firmly attached to the carboy box and the truck can now be pushed into place with its side base parts straddling the box and its trunnion seats respectively below the trunnions 40. When thus properly located, the crank arms 37 are rotated in the direction to lower the trunnions 40 into the seats 41 and elevate the box 10 sufficiently to be conveyed by the truck. By providing a plurality of the hooks 26 arranged vertically, the clamp becomes automatically adjustable for carboys of different height and whatever this variation may be, the trunnions 40 can be moved vertically into and out of seating engagement with the seats 41 of the truck.

Having thus described my invention, I claim:

1. A clamp for a carboy box of the type having spaced supports on the bottom thereof for respectively engaging sustaining surfaces, comprising a base dimensioned to pass under the box between

the supports without necessarily tilting or raising the box relative to such sustaining surfaces, standards attached respectively to the ends of said base, one of said standards at least being detachable, hook means on each standard, a head plate across the top of the box, latch levers respectively pivoted to said head for engaging said hook means, and means for locking said latch levers in holding engagement with said hook means.

2. A clamp for a carboy box of the type having spaced supports on the bottom thereof comprising a base dimensioned to pass under the box between the supports, standards attached respectively to the ends of said base, one of said standards at least being detachable, a head plate across the top of the box, releasable connecting means between said plate and said standards, threaded rods carried by the respective standards, bushings threaded respectively on said rods, trunnions respectively attached to said bushings, and means to operate said rods to raise and lower said trunnions.

3. In combination, a carboy box having downwardly extending spaced sills on the bottom thereof, a clamp comprising a base arranged to pass beneath the box and between said sills, and sides hinged thereto, a head plate across the top of the box, and means coacting with said sides and plate to anchor said clamp about said box.

4. In combination, a carboy box, a clamp, means for clamping said clamp about said box, a truck having elevated seats, trunnions carried by said clamp and positioned respectively above said truck seats when in position for mounting, and means on said clamp for moving said trunnions into and out of engagement with said seats.

5. In combination, a carboy box, a clamp, means for clamping said clamp about said box, a truck comprising a U-shaped base, to straddle said box, and skeleton side frames, each side frame having a trunnion seat, trunnions carried by said clamp and positioned respectively for vertical alinement with said seats when said truck is in straddled position, and means on said clamp for moving said trunnions into and out of engagement with said seats.

6. In combination, a carboy box, a clamp, means for clamping said clamp about said box, a truck comprising a U-shaped base, to straddle said box, and skeleton side frames, each side frame having a trunnion seat, trunnions carried by said clamp and positioned respectively for vertical alinement with said seats when said truck is in straddled position, means on said clamp for moving said trunnions into and out of engagement with said seats, and catches upon at least one of said standards for engaging said truck frames to prevent swinging of said box when supported by said truck.

MYRON BIXLER.
